UNITED STATES PATENT OFFICE.

WILLIAM G. VIALL, OF BRIDGEPORT, CONNECTICUT.

ROTOR FOR MOTORS.

1,126,594.

Specification of Letters Patent.

Patented Jan. 26, 1915.

Application filed March 9, 1912. Serial No. 682,675.

To all whom it may concern:

Be it known that I, WILLIAM G. VIALL, citizen of the United States, and resident of Bridgeport, in the county of Fairfield and State of Connecticut, have invented certain new and useful Improvements in Rotors for Motors, of which the following is a specification.

My invention refers to motors of the induction type and particularly to the operative member or rotors for alternating current motors.

The purpose of my invention is to produce an improved, simple and inexpensive form of rotor which can be easily stamped up from sheet metal and quickly assembled in a way to insure cheapness in construction, to further design the rotor in such a manner as to improve its general efficiency and durability, to lessen the number of parts and to finally produce a rotor which is well adapted to operate electric fans, and which is particularly suited to a simple and improved form of winding.

With these and other objects in view the invention resides and consists in the construction and novel combination and arrangement of parts hereinafter more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification, and upon which,

Figure 1, shows a perspective view of the assembled and specially formed plates constituting the core of my improved motor. Fig. 2, is a similar perspective view, of the rotor completed ready for placement in a motor frame. Fig. 3, is a detached plan view of the slotted copper binding plate shown attached to the rotor in Fig. 2. Fig. 4, is an edge view of the plate shown in Fig. 3. Fig. 5, shows a further plan and end view of a slightly modified form of copper binding plate. Fig. 6, is a side view of the binding plate shown in Fig. 5. Fig. 7, shows a detail cross sectional view across a part of the rotor showing the L-shaped slots with bridge pieces therein. Fig. 8, is an edge view, showing the means for connecting the adjoining ends of the binding plate, shown in Fig. 2. Fig. 9, is a central vertical longitudinal section through the rotor shown in Fig. 2. Fig. 10, is a detached perspective view of the binding plate rolled up and ready for attachment to the assembled core plates shown in Fig. 1, and Fig. 11, is a perspective view of an assembled rotor the projecting edges of the core and slots and bridges in binding plate being shown as arranged spirally, instead of straight as in the other views.

Referring in detail to the characters of reference marked upon the drawings, 12 represents a metal spindle upon which the other assembled parts of the rotor are mounted. The core of the rotor is made up of a series of metal disks 13 alike in construction and stamped from sheet iron, and are secured together by a tube and a single copper plate, without the use of solder. These stampings 13 are substantially round in form and are provided with a central hole 14 and a series of under cut notches 15 in their peripheral edge, thus forming a corresponding number of extended teeth 16. Said disks are lined up on the tubular bushing 17 as shown in Fig. 9, the ends of the bushing being turned out against the outer or end disks in a way to hold the disks together. The bushing in turn is formed or otherwise secured to the before mentioned spindle 12, in the manner shown in Fig. 9. The disks are carefully assembled so that the notches and teeth thereof properly register one with the other to form a series of longitudinal grooves and ribs in the face of the core, formed of the assembled disks, at corresponding intervals. These assembled soft iron disks constitute the core, which are first secured together by means of the tube before mentioned and are further held by means of a special form of copper plate 18, that is wound around, and fitted in the grooves of the core in a way to form a series of longitudinal copper members intermediate of the projected iron ribs and which are thus disposed parallel with the spindle. This binding plate will perhaps be best understood from Figs. 2 and 10, and includes cross slots 19, bridge portions 20 and side flanges 21 which latter is extended out slightly over the ends of the core, and its

edges may be rolled over upon itself to form an annular rib 22 upon each end to stiffen and strengthen the structure. The plate is rolled from the flat shape shown in Figs. 3 and 4 to the cylindrical form seen in Fig. 10 whereupon it is placed around the core and its ends tightly secured together to insure a firm fastening of the plate to the core. The preferred means of securing the ends 10 of the plate together is shown in Figs. 3, 4 and 10 and consists in forming extended tongues 23 on one end of the plate and suitable eyes 24 in the other end, and then simply threading the said tongues through 15 the eyes and bending them back under the plate. If desired, however, suitable eyes 25 may be formed in both ends of the plate in a corresponding position so that when the plate is rolled said eyes will aline with each 20 other to receive the uniting staples 26, as shown in Figs. 2 and 8. The notches in the peripheral edges of disks which form the 25 groove in the core, as before stated are undercut, or of an L shape, better to receive and retain the cylindrical plate member in position. This form of groove provides a 30 comparatively wide bottom to the groove such as will accommodate the flat form of bridge 20 and support the same in place against its centrifugal tendency to fly off 35 from the core when the rotor is in motion. The construction further insures the said bridge portion remaining below the surface of the ribs and thus within the grooves in the periphery of the rotor. The one edge 40 of these bridge portions is extended outwardly as shown in Figs. 3, 4 and 8 if desired to form outstanding flanges 27 and thereby to better conform to the shape of the groove and add metal and strength to the device.

If desired to form a motor with spirally disposed iron ribs, as shown in Fig. 11, it would be done by arranging the notches of 45 the respective plates, when assembling the same, so as to form the ribs and grooves spirally, and also forming the cross slots in the plate diagonally, so that when the plate is rolled to a cylindrical form the said slots 50 would conform to the spirally formed ribs and the bridge portions properly fit into the

spirally formed slots in the core as will readily be understood from Fig. 11.

Having thus described my invention what I claim and desire to secure by Letters 55 Patent is:

1. A rotor for alternating current motors, comprising a series of metal disks secured together and forming a core having a series of longitudinal L shaped grooves and ribs 60 in its peripheral surface, a single copper plate wound upon the core and provided with a series of slots to receive the ribs, a series of bridge portions to enter the grooves and provided with means to engage the 65 shoulders of the ribs, and means for securing the plate upon the core.

2. A rotor for alternating current motors, comprising a core having a series of longitudinal L-shaped grooves in its periphery, whereby to form intermediate ribs in the surface of the core, a single flexible copper plate encircling the core and provided with a series of cross slots and intermediate bridge portions, the slots receiving the ribs, 75 and the bridge portions fitting within the grooves, means arranged at the edge portions of the slots and fitting under the shoulders of the ribs, and means for connecting the ends of said plate. 80

3. A rotor for alternating current motors, comprising a core having a series of longitudinally extending L-shaped grooves in its periphery, whereby to form a plurality of longitudinal ribs the inner portions of 85 which are undercut, a single copper plate encircling the core and provided with a series of cross slots and intermediate bridge portions, said slots receiving said ribs, and said bridge portions fitting within said 90 grooves and into the undercut, outstanding flanges arranged in the grooves and between the rib portions, and means for connecting the ends of the copper plate together.

Signed at Bridgeport in the county of 95 Fairfield and State of Connecticut this 24th day of February A. D., 1912.

WILLIAM G. VIALL.
